Howard E. Thompson
ATTORNEY

UNITED STATES PATENT OFFICE.

JOSEPH SOSS, OF BROOKLYN, NEW YORK.

HINGE.

Application filed September 24, 1926. Serial No. 137,450.

This invention relates to hinges, and the object of the invention is to provide one or both parts or butts of a hinge with levers or other members actuated by the hinge movement, for example by the links of a hinge, for imparting movement to one or both of the bodies movably coupled by the hinge, or to impart movement to other bodies; a further object being to provide a hinge of the class and for the purpose specified adapted for use in connection with foldable leaves of a table whereby the leaves may be folded together and extended or moved into operative and inoperative positions, and the action of the hinge operating a lever coupled with one of the butts of the hinge; a further object of my invention is to utilize the leverage power of the working and movable parts of a hinge to actuate a device, mechanism or apparatus of any kind; and with these and other objects in view the invention consists in a device of the class and for the purpose specified which is simple in construction and operation, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a sectional view through the separate parts of a table leaf showing one form of my improved hinge construction and indicating the method of its use;

Fig. 2 is a view similar to Fig. 1 with the parts in a different position;

Fig. 3 is a section on the line 3—3 of Fig. 1;

Fig. 4 is a plan view of the adjacent ends of the separate parts of a table leaf indicating the position of my improved hinge coupled therewith;

Fig. 5 is a view similar to Fig. 1 but showing a slight modification; and,

Fig. 6 is a section on the line 6—6 of Fig. 5.

In the drawing I have shown for the purpose of illustrating one method of carrying my invention into effect, a table leaf 10 composed of separate parts 10^a and 10^b. Mounted in connection with the lower faces and

the abutting edges of the parts 10^a and 10^b are the separate butts 11 and 12 of a hinge made according to my invention, the hinges being set in mortises formed in the parts 10^a and 10^b and secured in position in any desired manner.

The separate butts 11 and 12, in the construction shown, are formed of sheet metal and are of channel formation in cross section, said butts having attaching flanges 13 at their adjacent faces when the parts are in the position shown in Fig. 1 of the drawing. Pivotaly mounted within the channel of the butt 11 as seen at 14 is a hinge link 15, the free end of which is provided with a pin 16 operated in elongated slots or grooves 17 formed in the opposite side faces of butt 12, while a similar link 18 is pivoted to the butt 12 as seen at 19 provided at its free end with a pin 20 operating in elongated slots or grooves 21 in the butt 11, the links 15 and 18 being substantially L-shaped in form and being pivoted together as seen at 22.

In practice, I provide separate butts 11 and 12 with spaced bearing portions 11^a and 12^a which project at right angles from said butts as clearly seen in Fig. 1 of the drawing, and to the outer ends of the bearing portions 11^a is pivoted a lever 23 as seen at 24 and a link 25 pivoted to one end of the lever and mounted upon the pin 20, whereby in the movement of said pin in the elongated grooves or slots 21 the link 25 transmits movement to the lever 23 to operate an anti-frictional roller 26 on the free end of the lever 23 in a guide channel or track 27, the form of which is such as to permit the separate parts 10^a and 10^b of the leaf 10 to drop below the surface of the table top when in closed position, and further to permit of the raising of the leaf parts into extended position and to support the same in common alinement with the table when extended for use of one or more of the extension leaves.

The hinge butt 12 is not provided with the lever 23 nor link 25 in the construction shown in Fig. 2, but if desired, it will be understood that a lever and link may be coupled with the bearing portion 12^a and used for any desired purpose, it being fur-

ther understood that a single lever and link construction may be mounted in connection with either one of the butts 11—12.

As above stated, the use of my invention

- 5 which is herein indicated is for supporting and operating the extension leaves of a table, and in Fig. 4 of the drawing I have indicated a plan view of the adjacent ends of the parts 10^a and 10^b of the table leaf 10 and 10 the butts of two hinges mounted at the side portions of said table leaf, both hinges being of the same construction, and the butts 11 of each hinge are provided with levers 23 having rollers 26 engaging two channels 27. 15 The structure of the channels 27 is such that when the table leaf is extended for use, as seen in Fig. 1 of the drawing, and moved from the position shown in Fig. 2 into such operative position, the leaf is slightly raised 20 and passes from the raised portion 27^a of the channels 27 and then drops into a slight depression 27^b to fixedly support and retain the leaf in proper position, it being understood that the end portions of the leaf parts 25 10^a and 10^b are supported on the extension rails 10^c of the table construction, said rails being indicated in Fig. 1 of the drawing. In moving the leaf 10, or the separate parts 10^a and 10^b to inoperative or folded position 30 as seen in Fig. 2 of the drawing, the part 10^a is raised and moved upwardly over and onto the part 10^b, in which operation the action of the hinge links 15 and 18, the link 25 and the lever 23 will cause the 35 lever 23 to be moved through the channel 27 to guide the parts 10^a and 10^b downwardly beneath the top of the table proper and between the extension rails 10^c. The completion of this operation is indicated in Fig. 2 40 of the drawing, and it will be noted that the lever 23 has been moved into position substantially at right angles to the longitudinal plane of the butt 11, when the separate butts are in their extended position.

- 45 In Figs. 5 and 6 of the drawing, I have shown a slight modification wherein the bearing portions 28 are arranged adjacent and at right angles to the end portions of the butts 11 and 12 instead of centrally thereof as seen in Fig. 1, and these bearing portions have grooves or apertures 29 which open into the grooves or apertures 17 and 21, and instead of employing the links 25, the levers 30 are mounted directly upon the 55 pins 16 and 20 operating in the apertures 17 and 21 respectively, whereby the action of the links 15 and 18 of the hinge is imparted directly to the levers 30, and said levers have, at the adjacent pivoted end thereof, pins 31 which operate in the apertures or grooves 29 whereby in the opening and closing of the hinge, the pins 31 travel toward and from the apertures 17 and 21, and the free ends of the levers 30 which are preferably provided with anti-frictional rollers 32

are moved laterally in opposite directions and into substantially parallel relation with the longitudinal plane of the separate butts of the hinge.

The construction shown in Figs. 5 and 6 of the drawing may be used for the same purpose as that indicated in Figs. 1 and 2 of the drawing. However, the parts 10^a and 10^b seen in Fig. 5 of the drawing may constitute two bodies of any kind or class coupled together by the hinge construction shown, and the movements of the levers 32 may be imparted to any device, apparatus or mechanism to accomplish a predetermined result. The distinctive feature of my present invention residing in utilizing the leverage power of the working and movable parts of a hinge to actuate a device, mechanism and apparatus of any kind, and while I have illustrated one method of carrying my invention into effect and have shown one form of hinge construction, it will be apparent that I am not necessarily limited in these respects, nor am I limited to the other details of construction herein shown and described, and various changes therein and modifications thereof may be made, within the scope of the appended claims, without departing from the spirit of my invention or sacrificing its advantages.

Having fully described my invention, what I claim as new and desire to secure by Letters Patent, is:—

1. The combination with a hinge comprising butt members movably coupled together by one or more links, of a member in operative connection with one of the links of the hinge whereby the opening and closing of the hinge will impart movement to said member.

2. The combination with a hinge comprising butt members movably coupled together by one or more links, of a member in operative connection with one of the links of the hinge whereby the opening and closing of the hinge will impart movement to said member, and said member being pivoted to one of the butts of the hinge.

3. In a hinge comprising two butts movably coupled together by links pivoted to the respective butts and to each other and movable relatively to opposed butts, a lever pivoted to one of said butts and in operative connection with the link movable relatively to said butt, whereby movement will be imparted to the free end of said lever in the operation of opening and closing said butts.

4. In a hinge comprising two butts movably coupled together by links pivoted to the respective butts and to each other and movable relatively to opposed butts, a lever pivoted to one of said butts and in operative connection with the link movable relatively to said butt, whereby movement will be im-

parted to the free end of said lever in the operation of opening and closing said butts, and a link disposed between said lever and the link of the hinge in connection with which the lever is coupled.

5. In a hinge comprising two butts movably coupled together by links pivoted to the respective butts and to each other and movable relatively to opposed butts, a lever

10 pivoted to one of said butts and in operative connection with the link movable relatively to said butt, whereby movement will be imparted to the free end of said lever in the operation of opening and closing said butts,

15 a link disposed between said lever and the link of the hinge in connection with which the lever is coupled, and means for guiding the first-named links in their movement relative to their respective butts.

20 6. A hinge for coupling and movably supporting the separate parts of a table leaf, comprising two butts, links for coupling said butts together, a lever in operative connection with one of the links of the hinge

25 and movable thereby to permit of the raising and lowering of said table leaf in a guide and support in the operation of folding and extending the separate parts of said leaf.

30 7. A hinge for coupling and movably supporting the separate parts of a table leaf, comprising two butts, links for coupling said butts together, a lever in operative connection with one of the links of the hinge and

35 movable thereby to permit of the raising and lowering of said table leaf in a guide and

support in the operation of folding and extending the separate parts of said leaf, said lever being pivotally supported in connection with one of the butts of the hinge.

40

8. A hinge for coupling and movably supporting the separate parts of a table leaf, comprising two butts, links for coupling said butts together, a lever in operative connection with one of the links of the hinge and movable thereby to permit of the raising and lowering of said table leaf in a guide and support in the operation of folding and extending the separate parts of said leaf, said lever being pivotally supported in connection with one of the butts of the hinge, and a link disposed between one end of the lever and the link for actuating said lever.

45

9. A hinge for coupling and movably supporting the separate parts of a table leaf, comprising two butts, links for coupling said butts together, a lever in operative connection with one of the links of the hinge and movable thereby to permit of the raising and lowering of said table leaf in a predetermined guide and support in the operation of folding and extending the separate parts of said leaf, said lever being pivotally supported in connection with one of the butts of the hinge, a link disposed between one end 55

50

of the lever and the link for actuating said lever, and means for guiding the last named link and hinge link in the butt of the hinge.

55

In testimony that I claim the foregoing as my invention I have signed my name this 21st day of Sept., 1926.

70
JOSEPH SOSS.
